SEND/RECEIVE DATA PRINTER TERMINAL

Robert H. Van Valkinburgh, Pittsford, and Robert A. Clowe, Penfield, N.Y., assignors to Xerox Corporation, Stamford, Conn.

Filed May 20, 1970, Ser. No. 23,109

Term of patent 14 years

Int. Cl. D14—02

U.S. Cl. D26—5

FIG. 1

FIG. 2

FIG. 3

FIG. 4

FIG. 5

FIG. 1 is a side elevational view of a send/receive data printer terminal showing our new design;

FIG. 2 is an elevational view taken from the side opposite that shown in FIG. 1;

FIG. 3 is a front elevational view thereof;

FIG. 4 is a top plan view thereof; and

FIG. 5 is a rear elevational view thereof.

We claim:

The ornamental design for a send/receive data printer terminal, as shown.
